Filed Mar. 19, 1969, Ser. No. 16,328

Term of patent 14 years

Int. Cl. D9—99
U.S. Cl. D9—291

FIG. 1.

FIG. 2.

FIG. 3.

FIG. 1 is a perspective view of a hook support for a carrier bag handle showing our new design; and

FIG. 2 is an elevational view taken from one side thereof; and

FIG. 3 is an elevational view taken from the side opposite that shown in FIG. 2.

The fragmentary broken line representation of a carrier bag in FIGS. 1 through 3 is for purposes of illustration only.

We claim:

The ornamental design for a combined closure and handle for a carrier bag, as shown and described.
